UNITED STATES PATENT OFFICE.

AUGUST ZWOBODA, OF NEW YORK, N. Y.

PRINTING PRESS.

Application filed February 24, 1921. Serial No. 447,442.

To all whom it may concern:

Be it known that I, AUGUST ZWOBODA, a citizen of the United States, and resident of the borough of Bronx, in the city and State 5 of New York, have invented a new and useful Improvement in Printing Presses, of which the following is a specification.

This invention relates to that class of printing presses in which the printing plates 19 or forms are mounted on an endless carrier traveling in an elongated path, said carrier being arranged to bring successive printing forms into engagement with their respective impression surfaces with a rolling contact, said invention being suitable for use 15 either in connection with direct or transfer printing mechanisms.

The object of my invention is to provide certain improvements in the construction, 20 form, arrangement and operation of the several parts of both the printing and the inking mechanisms, whereby all lost motion in the drive of said mechanisms is eliminated; in which the mechanisms are capable of 25 great speed and are well adapted, with slight changes, for single or multi-color work, and by means of which a completed picture in perfect register of any number of colors may be produced, in one cycle of the 30 press.

My invention more particularly includes the provision of overlapping racks on the links of the side chains of the endless carriers, whereby the driving gears will never 35 be disengaged from the racks as the successive links pass the driving gears. My invention also includes a novel arrangement of the parts of the inking mechanism, whereby the working-up rollers for the inking 40 rollers are positively rotated by the movement of the endless carrier thus forming a very simple and effective means for working up the ink on the inking rollers, as the inking rollers pass about half way of 45 their orbit from the point where they are engaged by their ductor rollers to the point where they engage their respective printing forms.

A practical embodiment of my invention 50 is represented in the accompanying drawings, in which

Fig. 1 represents in top plan so much of an offset printing press as will include my invention.

Fig. 2 represents a longitudinal section

taken in the plane of the line II—II of Fig. 1.

Fig. 3 represents a transverse vertical section through the inking mechanism taken in the plane of the line III—III of Fig. 2, 60 looking in the direction of the arrows, and

Fig. 4 represents a transverse vertical section through the printing mechanism taken in the plane of the line IV—IV of Fig. 2, 65 looking in the direction of the arrows.

The base of the printing press is denoted by 1, and the side frames which uprise therefrom by 2. A blanket cylinder 3 has its shaft 4 mounted in suitable bearings in the side frames 2.

The printing forms are denoted by 5 and their cross supports by 6. The endless carrier for the printing forms comprises two side chains, the links 7 of which are provided along their inner edges with overlapping racks 8. These side chains are located in close proximity to the side frames 2, and the cross bars 9, which form the pivots for the links of both of the side chains, project outwardly beyond the side chains and are 75 there provided with studs or rollers 10 which are located in and fitted to travel along corresponding vertically elongated endless grooves 11 which form ways or tracks for the said studs or rollers 10.

A driving shaft 12 is mounted in suitable bearings in the side frames 2, which driving shaft is provided with gears 13 meshing with the overlapping racks 8 of the side chains of the endless carrier for driving the 90 endless carrier. The driving shaft 12 is located in substantially the same horizontal plane as the shaft 4, and the driving gears 13 mesh with the overlapping racks of the side chains at diametrically opposite points 95 so that each side chain is positively driven at two points.

The relative positions of the parts are such that the printing forms will be brought successively into rolling contact with the 100 cylinder 3.

I will now proceed to describe the inking mechanism for the printing forms:

The groups of inking rollers are herein shown as arranged in two pairs 14 and 15, 105 each pair having its working-up rollers 16 and 17 respectively, which inking and working-up rollers extend across the machine and are suitably mounted in corresponding links 18 of an endless carrier comprising 110

two side chains, the inner edges of the links of which are provided with overlapping racks 19.

The cross bars 20, which form the pivots 5 for the links of the two side chains and on which the working-up rollers are mounted, project outwardly beyond the side chains and are there provided with studs or rollers 21 which are located in and are fitted to 10 travel along corresponding vertically elongated endless grooves 22 in the side frames. Those cross bars 20 on which the working-up rollers are mounted are provided with pinions 20* which mesh with endless racks 22*, 15 corresponding in contour with the endless grooves 22, for positively driving the working-up rollers as the endless carrier is driven. A driving shaft 23 extends across the machine and is mounted in suitable bearings 20 in the side frames 2. This cross shaft is provided with two driving gears 24 which mesh at diametrically opposite points with the overlapping racks 19 for driving the racks at two points. This cross driving shaft 25 is located in substantially the same horizontal plane as the cross driving shaft 12 and the cross shaft 4.

The relative positions of the parts are such that the groups of inking rollers 14, 30 15 are brought into rolling contact with the faces of their respective inking forms 5, it being understood that the groups of rollers are traveling in the opposite direction from their forms at the time of contact.

35 In the embodiment shown in the accompanying drawings, there are four printing forms provided and there are four groups of inking rollers provided, one group of inking rollers for each form.

40 I have shown four ink fountains 25 and their fountain rolls 26 which fountain rolls may be driven step by step by any well-known or approved means, not shown herein.

45 I have shown four ductor rollers 27, one for each fountain roll, which ductor rollers are herein shown as moved alternately into and out of contact with their respective groups of inking rollers and their respective fountain rolls by four cams 28 interconnected by a train of gears 29. The several ink fountains may carry ink of one color or they may carry inks of different colors, according to the use to which the 50 printing press is to be placed.

The ductor operating cams 28 are driven from the shaft 23 at the required speed by providing the shaft 30 of one of the cams with a beveled gear connection 31, 32 with 60 a short longitudinal shaft 33, which last named shaft has a beveled gear connection 34, 35 with the driving shaft 23.

The driving shaft 23 may be driven from the driving shaft 12 at the required speed 65 by providing the shaft 23 with a gear 36

which meshes with an idler gear 37 which in turn meshes with the gear 38 on the shaft 12.

The driving shaft 12 may be driven from the cylinder shaft 4 by the meshing of the gear 38 with the gear 39 carried by the 70 shaft 4.

From the above description it will be seen that I have provided means whereby a very rapid printing may be obtained either in single or multi-color work, the construction, 75 form and arrangement of the several parts being such that a continuous interconnected even drive of the several parts is obtained; the lost motion usually incident to the driving of endless carriers being eliminated and 80 the arrangement of the parts being such that a true and even rolling contact is obtained between the inking rollers and their forms, and between the forms and their impression surface.

85 It will also be seen that I have provided a very simple means whereby the press may be changed from a single to a multi-color press without an undue change in the parts.

It is evident that various changes may be 90 made in the construction, form and arrangement of the several parts without departing from the spirit and scope of my invention; hence I do not wish to limit myself to the particular embodiment herein shown and 95 described but,

What I claim is:

1. In a printing press, a group of inking rollers, an endless carrier therefor comprising side chains having overlapping racks, 100 a driving shaft having gears meshing with said racks, and means driven from said shaft for supplying ink to the inking rollers.

2. In a printing press, a plurality of groups of inking rollers, an endless carrier 105 therefor comprising side chains having overlapping racks, a driving shaft having gears meshing with said racks, and means driven from said shaft for supplying ink to the groups of inking rollers.

3. In a printing press, a plurality of groups of inking rollers, an endless carrier therefor comprising side chains having overlapping racks, a driving shaft having gears meshing with said racks, and means 115 driven from said shaft for supplying different colored inks to successive groups of inking rollers.

4. In a printing press, side frames having corresponding endless grooves, a plurality 120 of groups of inking rollers, a traveling endless carrier therefor comprising side chains having rollers located in said grooves for guiding the carrier, and means for supplying different colored inks to successive 125 groups of inking rollers.

5. In a printing press, side frames having corresponding endless grooves, a group of inking rollers, an endless carrier therefor comprising side chains having rollers lo- 130

- cated in said grooves for guiding the carrier and also having overlapping racks, a driving shaft having gears meshing with said racks, and means driven from said shaft for supplying ink to the inking rollers.
6. In a printing press, side frames having corresponding endless grooves, a plurality of groups of inking rollers, an endless carrier therefor comprising side chains having rollers located in said grooves for guiding the carrier and also having overlapping racks, a driving shaft having gears meshing with said racks, and means driven from said shaft for supplying ink to said groups of inking rollers.
7. In a printing press, side frames having corresponding endless grooves, a plurality of groups of inking rollers, an endless carrier therefor comprising side chains having rollers located in said grooves for guiding the carrier and also having overlapping racks, a driving shaft having gears meshing with said racks, and means for supplying different colored inks to successive groups of inking rollers.
8. In a printing press, side frames having corresponding endless grooves, a group of inking rollers, a traveling endless carrier therefor comprising side chains having rollers located in said grooves for guiding the carrier, means for supplying ink to said inking rollers, and positively rotated working-up rollers for said inking rollers.
9. In a printing press, an ink fountain, a ductor roller, a group of inking rollers, an endless carrier therefor comprising side chains having overlapping racks, a driving shaft having gears meshing with said racks, and means driven from said shaft for periodically moving the ductor roller into and out of contact with the inking rollers.
10. In a printing press, ink fountain, ductor rollers, a plurality of groups of inking rollers, an endless carrier therefor comprising side chains having overlapping racks, a driving shaft having gears meshing with said racks, and means driven from said shaft for periodically moving the ductor rollers into and out of contact with their respective groups of inking rollers.
11. In a printing press, side frames having corresponding endless grooves, an ink fountain, a ductor roller, a group of inking rollers, a traveling endless carrier therefor comprising side chains having rollers located in said grooves for guiding the carrier, and means for periodically moving the ductor roller into and out of contact with the inking rollers.
12. In a printing press, side frames having corresponding endless grooves, ink fountains, ductor rollers, groups of inking rollers, a traveling endless carrier therefor comprising side chains having rollers located in said grooves for guiding the carrier, and means for periodically moving the ductor roller into and out of contact with the inking rollers.
13. In a printing press, side frames having corresponding endless grooves, an ink fountain, a ductor roller, a group of inking rollers, a traveling endless carrier therefor comprising side chains having rollers in said grooves for guiding the carrier and also having overlapping racks, a driving shaft having gears meshing with said racks, and means driven from said shaft for periodically moving the ductor roller into and out of contact with the inking rollers.
14. In a printing press, side frames having corresponding endless grooves, ink fountains, ductor rollers, groups of inking rollers, a traveling endless carrier therefor comprising side chains having rollers in said grooves for guiding the carrier and also having overlapping racks, a driving shaft having gears meshing with said racks, and means driven from said shaft for periodically moving the ductor rollers into and out of contact with their respective groups of inking rollers.
15. In a printing press, a printing form, an endless carrier therefor comprising side chains having overlapping racks, and a driving shaft having gears meshing with said racks.
16. In a printing press, a printing form, an endless carrier therefor comprising side chains having overlapping racks, a driving shaft having gears meshing with said racks, and means driven from said shaft for applying ink to said printing form.
17. In a printing press, a plurality of printing forms, an endless carrier therefor comprising side chains having overlapping racks, and a driving shaft having gears meshing with said racks.
18. In a printing press, a plurality of printing forms, an endless carrier therefor comprising side chains having overlapping racks, a driving shaft having gears meshing with said racks, and means driven from said shaft for applying ink to the printing forms.
19. In a printing press, a plurality of printing forms, an endless carrier therefor comprising side chains having overlapping racks, a driving shaft having gears meshing with said racks, and means driven from said shaft for applying different colored inks to successive printing forms.
20. In a printing press, side frames having corresponding endless grooves, a plurality of printing forms, an endless carrier therefor comprising side chains having rollers located in said grooves for guiding the carrier and also having overlapping racks, and a driving shaft having gears meshing with said racks.
21. In a printing press, side frames having corresponding endless grooves, a plu-

rality of printing forms, an endless carrier therefor comprising side chains having rollers located in said grooves for guiding the carrier and also having overlapping racks, a driving shaft having gears meshing with said racks, and means driven from said shaft for applying ink to the printing forms.

22. In a printing press, side frames having corresponding endless grooves, a plurality of printing forms, an endless carrier therefor comprising side chains having rollers located in said grooves for guiding the carrier and also having overlapping racks, a driving shaft having gears meshing with said racks, and means driven from said shaft for applying different colored inks to successive printing forms.

23. In a printing press, a plurality of printing forms, an endless carrier therefor comprising side chains having overlapping racks, a driving shaft having gears meshing with said racks, a group of inking rollers, an endless carrier therefor comprising side chains having overlapping racks, a driving shaft having gears meshing with said racks, and means for supplying ink to the inking rollers.

24. In a printing press, a plurality of printing forms, an endless carrier therefor comprising side chains having overlapping racks, a driving shaft having gears meshing with said racks, a group of inking rollers, an endless carrier therefor comprising side chains having overlapping racks, a driving shaft having gears meshing with said racks, and means for supplying ink to the inking rollers, said driving shafts and ink supplying means being interconnected.

40 25. In a printing press, a plurality of groups of inking rollers, an endless carrier therefor comprising side chains having overlapping racks, a driving shaft having gears meshing with said racks, ink fountains, their ductor rollers, and a plurality of interconnected cams driven from the driving shaft for moving the ductor rollers into and out of contact with their respective groups of inking rollers.

50 26. In a printing press, groups of inking rollers, an endless carrier therefor comprising side chains having overlapping

racks, and driving gears meshing with said racks.

27. In a printing press, a plurality of 55 printing forms, an endless carrier therefor comprising side chains having overlapping racks, and driving gears meshing with said racks.

28. In a printing press, a plurality of 60 printing forms, groups of inking rollers therefor, endless carriers for the printing forms and the inking rollers respectively, each of said endless carriers comprising side chains having overlapping racks, and 65 driving gears meshing with said racks.

29. In a printing press, side frames having corresponding endless grooves, a group of inking rollers, a traveling endless carrier therefor comprising side chains having 70 rollers located in said grooves for guiding the carrier, endless racks following the contour of said grooves, and working-up rollers for said inking rollers, said working-up rollers having pinions meshing with said 75 endless racks.

30. In a printing press, side frames having corresponding endless grooves, a plurality of groups of inking rollers, a traveling endless carrier therefor comprising side 80 chains having rollers located in said grooves for guiding the carrier, endless racks following the contour of said grooves, and working-up rollers having pinions meshing with said endless racks.

85 31. In a printing press, a blanket cylinder, a plurality of printing forms arranged to coact therewith, an endless carrier for said printing forms comprising side chains having overlapping racks, driving gears meshing with said racks, and means for applying ink to said printing forms.

32. In a printing press, a blanket cylinder, a plurality of printing forms arranged to coact therewith, an endless carrier for 95 said printing forms comprising side chains having overlapping racks, driving gears meshing with said racks, and means for applying different colored inks to successive printing forms.

100 In testimony, that I claim the foregoing as my invention, I have signed my name this 10th day of February 1921.

AUGUST ZWOBODA.
